PENCIL

Kay Miller, New Brunswick, and Howard P. Smith, Leonia, N. J., assignors to Joseph Dixon Crucible Company, Jersey City, N. J., a corporation of New Jersey

Application July 18, 1940, Serial No. 346,136

2 Claims. (Cl. 120—83)

The invention relates to an improvement in sheaths or casings for elongated implements of relatively small diameter or cross section adapted to be consumed or worn away in use. Such implements include pencils, erasers, cosmetic and toilet preparations, sharpening stones for engravers, dental devices, and many other similar implements in familiar use. It is common practice to enclose these implements in a sheath or casing of wood or paper leaving a small portion of one end of the core of the implement exposed for use. When the exposed portion of the core has been consumed or worn away, a fresh portion of the core is exposed for use by removing a portion of the adjacent end of the sheath. If the sheath is composed of wood this is usually done by means of a knife or by means of a mechanical "pencil sharpener." If the sheath is composed of paper, it usually consists of a weakly-connected series of coiled strips which are removed one at a time to expose the core. The wooden sheath is more universally employed, especially as a casing for pencils, the paper sheath consisting of spirals of removable strips having a more restricted use for special purposes. The present invention is more particularly concerned with an improvement in sheaths suitable for cutting by means of a knife or a machine. Since the pencil consisting of a core of marking material such as graphite or crayon enclosed in a sheath of wood or paper is typical of all the sheathed, elongated, consumable implements mentioned above, the term "pencil" will be used generically herein to designate the implement, improvement in the sheath of which is the subject-matter of the invention.

Certain kinds of wood, especially those popularly known as "ceder," whether true cedars or not, have proven satisfactory for use as sheaths for pencils with respect to lightness, ease of manufacture into sheaths and easy cutting or shaving qualities. But cedar or other wood suitable for pencil sheaths presents certain disadvantages: Increasing labor costs involved in present methods of manufacture; the rising cost of perfect, straight-grained wood; the presence of a large percentage of cross-grained wood mixed with the straight-grained wood, thereby entailing waste; and the liability of the wood to attack by fungus growths, not always possible to detect before manufacture and which results in the weakening of the wood. Moreover, the pencil sheath consists of two halves, and it is a difficult, if not impossible task to match accurately as to grain the slats or slabs from which

the sheath halves are made. If the grains of the opposed slats differ too much, the resulting uneven expansion of the pencil halves due to absorption and emission of moisture frequently entails waste in the form of pencils too crooked to be marketed. A further waste in the present method of manufacture of wood pencil sheaths in hexagonal, cylindrical, or other cross-sectional contour is caused by the fact that the sheaths are made from solid blocks of wood which must be first grooved to receive the core or marking material, and thereafter the exterior of the pencil must be milled or otherwise machined to give the pencil the desired cross-sectional shape. As a result of these and other drawbacks to the use of wood for pencil sheaths, it has been proposed to use cheaper substitutes having all the good qualities of wood without its disadvantages, but up to the present invention, so far as we are aware, these proposals have not resulted in commercially-adapted pencil sheaths.

The object of the invention is to provide the core of elongated, consumable implements, such as the marking material of pencils, with a sheath having all the advantages of the sheaths composed of high grade, straight-grained wood, but which can be produced at a cost much less than the cost of wood sheaths. To this end, the invention consists in wrapping around the core of the implement a strip of appropriate flexible sheet material substantially as wide as the core is long, and interposing between the convolutions or spirals of the flexible sheet material a thin layer of adhesive, so that the roll of flexible sheet material with the interposed roll of adhesive together constitute a solid body, the adjacent, individual spirals or convolutions of the flexible sheet material being inseparably connected with each other by means of the adhesive. Several kinds of flexible sheet material may be used, such as paper, Cellophane, cellulose acetate, and like materials of relatively low density and high strength, but we have found paper the cheapest and most satisfactory. Any kind of soft, flexible paper is suitable for the purpose, but we prefer to use the kind of paper known as "newsprint." Newsprint paper of the type we prefer to use is a standard product made from about 80% of ground wood pulp and 20% of sulphite pulp, weighing 32 lbs. per ream, which is about 3000 square feet.

The sheath composed of alternate layers or convolutions of newsprint paper and an appropriate adhesive binding the adjacent layers or convolutions of the paper inseparably together,

can readily be cut or "sharpened" by means of a sharp knife blade. The cut surface will be smooth and entirely free from uncut fibers or shreds. When however, it is attempted to cut such a sheath in a rotary pencil sharpener the blades of which have become dulled by reason of long use, it is found that the freshly cut surface of the sheath presents uncut shreds or fibers of the wood or sulphite pulp. In order that the newsprint paper and adhesive sheath may be readily and smoothly cut by means of even a dull rotary pencil sharpener blade, the fibers of the newsprint paper are embrittled by subjecting the newsprint paper to partial charring or destructive distillation, either by means of heat or chemical action. The degree to which partial charring of the paper is carried will depend upon the toughness of the fibers of which the paper is composed and the tensile strength of the charred paper. The greater the degree of charring, of course, the easier it will be to cut the sheath, but at the same time, the greater the degree of charring, the less tensile strength the paper will have. Accordingly, the degree to which the paper should be charred, either by the application of heat or chemical action, may be readily determined by leaving in the paper sufficient tensile strength to serve as a satisfactory sheath, it having been found that when the paper has not been too greatly weakened the fibers have been sufficiently embrittled so that they may be smoothly cut, even by a dull spiral sharpener blade. Usually treatment of the paper at 200 degrees C. for five minutes will sufficiently embrittle the paper for its intended purposes.

Several kinds of adhesives may be employed, such as dry animal glue dissolved in a glue to water ratio of approximately 1 to 2, which is applied at a temperature of substantially 130° F. We prefer, however, to use sodium silicate of an alkali-silicate ratio of about 1 to 3.22 diluted with water to a specific gravity of 1.3. Such adhesive functions at normal room temperature as a satisfactory bond for inseparably binding together adjacent spirals or convolutions of the roll of sheet material so that the completed sheath is substantially a solid body resembling in all its functions a sheath composed of high grade cedar wood.

To form the improved sheath consisting of alternate layers or convolutions of flexible sheet material and adhesive, one side of the sheet material is completely covered with the liquid adhesive so that when the core is applied to the margin of one end of the adhesive-covered surface of the sheet material and the margin of the sheet material is wrapped around the core, the core is thereby fastened or glued to the sheet material, so that in the completed implement the core is immovable relatively to the sheath. As the rolling of the core in the adhesive-coated sheet material is continued, the adhesive is, of course, spread onto the uncoated surface of the sheet material, so that both sides of the sheet material are fully coated with the adhesive with the result that in the completed sheath there is a thin layer of adhesive between the adjacent layers or convolutions of the sheet material. This layer or convolution of adhesive is so thin that for all practical purposes the adjacent layers or convolutions of the sheet material abut each other. When paper is chosen as the sheet material, it is understood that the paper is sufficiently porous to permit the adhesive to pene-

trate a substantial distance into the sheet from both sides thereof to lock the adjacent layers of sheet material together. As an illustration of the weight relation between the components of a sheath which possesses desirable characteristics we give the following, based on the dried material: treated newsprint paper, 84 percent; sodium silicate 16 percent.

In the accompanying drawing illustrating the invention as applied to a pencil, Fig. 1 is a perspective view of the core of marking material and of the flexible sheet material in which the core is to be wrapped; Fig. 2 is an end elevational view showing the sheet material partially wrapped around the core; Fig. 3 is a side elevation of the pencil showing the sheet material fully wrapped around the core; Fig. 4 is a side elevation of the completed pencil, and showing one end of the sheath cut away to expose a portion of the core of marking material for use; Fig. 5 is a transverse section on an enlarged scale through the pencil shown in Figs. 3 and 4; Fig. 6 is a side elevation, partly in section, of a pencil having a modified form of sheath; and Fig. 7 is a transverse section of the pencil shown in Fig. 6.

To produce the improved pencil, or other implement having a consumable core, of the present invention, the core, indicated at 10, is wrapped tightly in a sheath consisting of a sheet of appropriate flexible material 11, for example, newsprint paper, coated with a layer of adhesive 12 in a wet or sticky condition. In Fig. 2 is shown the step of winding the adhesive-coated flexible sheet material tightly around the core 10. It will be understood that the sheet material may be a continuous strip, as shown in Figs. 1 and 2, or that it may be in sections. It is sometimes desirable, depending on how fast the kind of adhesive used dries, to divide the sheet material transversely into two or more sections and separately wrap the adhesive-coated sections around the core, permitting the adhesive on one section to dry before the next succeeding section is applied to the partially wrapped core. Since the sheet of flexible material is entirely coated on at least one side with the wet or sticky adhesive before it is wrapped around the core, it will be understood that the inner spiral or convolution 35 of the sheath adheres tightly to the core, so that in the completed pencil 13, the core of marking material is immovable relatively to the sheath.

Moreover since the adhesive serves when dry to bind adjacent layers or convolutions of the flexible sheet material inseparably together, the alternate layers of sheet material and adhesive become, for the practical purpose of serving as a sheath for a consumable core, a substantially homogeneous body, the layers of adhesive being so thin that the layers of sheet material seem to the unaided eye to be transversely a continuous body. For the purposes of illustration, however, since the adhesive is an essential part of the sheath, the layer of adhesive 12 is indicated in the sectional views by the division or boundary lines 12 in Fig. 5 and in Fig. 7.

The relations between stiffness, density, cutting qualities and such physical properties of the sheath structure can be varied by controlling either the proportion of adhesive to sheet material or the character of these components. It is often desirable to exert this control so that the finished sheath will best suit any special conditions under which the consumable core implement may be used. Thus, if it is desirable to re-

duce density, a sheet material is selected which will introduce small, dispersed voids or air spaces into the finished sheath structure.

For example, when a sheath of minimum overall density is produced, the sheath is made up in a plurality of sections as described above one or more of the sections being characterized by the inclusion of dispersed voids or air spaces. As an instance, the sheath may be made in three sections, the inner section immediately enclosing the core and the outermost section being composed of alternate layers of smooth paper or other sheet material and adhesive, and the intermediate section, that interposed between the inner and the outermost sections, being so formed that it contains air spaces. In the modified form of the invention shown in Figs. 6 and 7, the inner core-enclosing section 15 and the outermost section 16 are composed of alternate layers or convolutions of smooth paper and adhesive, wound tightly together so that there are no air spaces between the layers, whereas the layers of the intermediate section 17 contain air pockets 18 which may be variously formed in the structure, as by substantially regularly indenting one or both surfaces of the paper. Although in the step of wrapping the paper or other flexible sheet material around the core the adhesive is applied to both surfaces of the sheet material, it will be obvious that the contact between adjacent layers of the sheet material will be only at the raised points produced by forming the recesses, whereby there will exist a relatively large area of air spaces between two adjacent layers of section 17, thereby lessening materially the weight of the sheath.

The method of wrapping the corrugated paper of Figs. 6 and 7 around the inner sheath sections is that followed in wrapping an adhesive-covered smooth sheet about the inner section in those cases where the sheath consists of a plurality of sections of smooth paper or other smooth, flexible sheet material.

While the sheath materials are herein illus-

trated as being of circular outline in cross-section, it is to be understood that we do not limit ourselves to this contour since the materials may be produced in or reduced to other acceptable cross-sectional outlines, such as hexagonal or oval.

The elongated core of consumable material having been covered with the sheath, as described above, composed of alternate layers of flexible sheet material and adhesive binding adjacent layers of sheet material inseparably together, the outer surface of the outermost layer of sheet material may be covered with enamel or other suitable, attractive coating.

Having thus described the invention what we claim as new is:

1. As an article of manufacture, an implement comprising an elongated consumable core and a sheath enclosing the core consisting of flexible sheet material wound around the core and a layer of adhesive between the convolutions of sheet material holding them inseparably together, said sheet material being characterized by the fact that it is composed of paper a portion at least of which has its surfaces substantially-regularly indented.

2. As an article of manufacture, a pencil comprising a core of marking material and a sheath enclosing the core consisting of newsprint paper wrapped around the core and a layer of dried sodium silicate interposed between the convolutions of the newsprint paper holding them inseparably together, said sheath being characterized by the fact that it consists of three sections of convolutions, the first section immediately around the core being composed of smooth newsprint, the convolutions of the second section wound around the first section being composed of newsprint paper, the surfaces of which are substantially-regularly indented, and the third section wound around the second section being composed of smooth newsprint paper.

KAY MILLER.
